HIGHWAY CROSSING

William C. Hedcock, Wilmette, Ill., assignor to
 American Steel Foundries, Chicago, Ill., a corporation of New Jersey

Application March 13, 1933, Serial No. 660,491

21 Claims. (Cl. 238—8)

The present invention relates to railway crossings and the like.

Among the objects of the present invention is to provide a novel railway crossing including a plurality of crossing members adapted to provide a smooth crossing, and one which is particularly adapted to withstand the present-day heavy truck loads.

Another object of the present invention is to provide a novel railway crossing comprising a plurality of interchangeable crossing members, thus facilitating the easy assembly of said crossing and removal thereof when track repairs are necessary, as likewise to provide for the easy replacement of individual members when necessary.

The present invention comprehends the idea of providing a novel railway crossing comprising a plurality of crossing members adapted to be secured in place in wedging engagement with the track rails. More particularly, the present invention contemplates the idea of providing a plurality of crossing members having means for engaging beneath the head of the track rails, these crossing members being adapted to be moved into and secured in an operative position in wedging relation with the track rail.

Still another object of the present invention is to provide a novel railway crossing in which the members forming the same are adapted for use with rails of various heights, suitable supporting means being used therewith whereby the crossing members are disposed in their operative position in wedging relation with these rails.

A still further object of the present invention is to provide a railway crossing comprising a series of crossing members disposed adjacent the inner edge of the track rails and which are provided with novel means for retaining insulating means disposed therebetween.

A still further object of the present invention is to provide an improved railway crossing which is inexpensive to make and maintain, one which will not interfere with track circuits and one which fulfills all requirements of manufacture and service.

Another object within the purview of the present invention is to provide a novel crossing between tracks which may comprise a plurality of members incorporating the structure of the crossing members used between the rails of each of the tracks, these crossing members being suitably secured in position and at the correct elevation to provide a smooth crossing between these tracks for the passage of heavy loads thereover.

55 Other objects, features, capabilities and advan-

tages are comprehended by the invention, as will later appear and as are inherently possessed thereby.

Referring to the drawings:

Figure 1 is a fragmentary top plan view of a 5 railway crossing made in accordance with the present invention;

Figure 2 is a fragmentary view in cross-section taken in a plane represented by line 2—2 of Figure 1 of the drawings;

Figure 3 is a fragmentary view in elevation taken in the plane represented by line 3—3 of Figure 1 of the drawings;

Figure 4 is an enlarged fragmentary view in cross-section taken in the plane represented by line 4—4 of Figure 1 of the drawings;

Figure 5 is an enlarged fragmentary view in cross-section taken in the plane represented by line 5—5 of Figure 1 of the drawings;

Figure 6 is an enlarged fragmentary view in cross-section taken in the plane represented by line 6—6 of Figure 1 of the drawings;

Figure 7 is a fragmentary top plan view of a railway crossing made in accordance with the present invention and disclosing an alternative construction for the crossing members thereof;

Figure 8 is a fragmentary view in cross-section taken in the plane represented by line 8—8 of Figure 7 of the drawings;

Figure 9 is a fragmentary view in cross-section taken in the plane represented by line 9—9 of Figure 7 of the drawings;

Figure 10 is a fragmentary view in cross-section taken in the plane represented by line 10—10 of Figure 7 of the drawings;

Figure 11 is a fragmentary view in cross-section disclosing the present invention embodied in a crossing between railway tracks;

Figure 12 is a fragmentary view in cross-section similar to that of Figure 11 of the drawings, disclosing an alternative construction for the crossing between tracks;

Figure 13 is a fragmentary view in cross-section similar to Figures 11 and 12, disclosing a further alternative construction for the crossing between tracks;

Figure 14 is a fragmentary view in cross-section of a crossing member as disclosed in Figures 11 to 13 inclusive, disclosing its engagement with the rails of the tracks; and

Figure 15 is a fragmentary view in cross section disclosing the connection of adjacent crossing members disclosed in Figures 11 to 13 inclusive of the drawings.

Referring now more in detail to the drawings,

an embodiment of the present invention is disclosed in connection with a multiple track crossing, including the railway tracks generally referred to as 2 and 4, although it is of course understood that the same is designed for use in a single track crossing. These railway tracks 2 and 4 are of similar construction and of conventional design, and comprise spaced rails such as 6 and 8, supported upon the spaced ties, such as 10, 12 and 14, and secured thereto, as by means of spikes 16. These rails may be any of the standard weights, and are formed with a head 18, a vertically disposed web 20, and laterally extending flanges 22 and 24.

15 The railway crossing made in accordance with the present invention, and generally referred to as 26, comprises a series of crossing members 28 disposed adjacent the inner edge of each of the rails 6 and 8, and a series of crossing members 30 disposed adjacent the outer edge of each of the rails 6 and 8. The crossing members 28 of the series adjacent the inner edge of each of the rails 6 and 8 are of similar construction and are interchangeable one with the other, thereby 25 providing an arrangement whereby the individual members may be removed and replaced, when necessary, with great ease. These crossing members 28 are formed with a top plate 32 provided with upstanding anti-skid means, such as 30 buttons 34, or the like, the top plate 32 being provided with marginal depending flanges or legs 36 for reinforcing the same. If desired, the plate 32 may be further reinforced by means of a depending flange or web 38 extending between opposite depending flanges 36.

These crossing members 28 have their edge, at the inner or gauge edge of the rails, formed with a channel 40 to provide clearance for wheel flanges of passing trains. This channel 40 at 40 spaced intervals is further provided with lugs or extensions 42 adapted to engage under the rail head 18 for a purpose to be later more fully disclosed.

The crossing members 28 of the two series disposed adjacent the rails 6 and 8 are supported along one edge thereof as by means of the central stringer 44 and stringers 46 and 48 disposed adjacent the rails 6 and 8, respectively, these stringers 44, 46 and 48 being secured to the ties, 50 such as 10, 12 and 14, as by means of the spikes 52 and the like. Each of the crossing members 28 adjacent the channel 40, as well as adjacent the depending leg 36 oppositely disposed thereto, is formed with a plurality of spaced pockets 52, 55 each of which is formed with a lower wall 54 providing a supporting surface for supporting these plates on the stringers. These crossing members 28, under ordinary conditions, are maintained in their operative position by the screw spikes 56 disposed in the pockets 52 and which threadedly engage in the stringer 44. However, in case of an interfering rail joint, the lugs or extensions 42 may be removed and the crossing members at that point fastened to the stringers adjacent 65 either the rail 6 or 8 by means of screw spikes 56 disposed in the pockets 52 at that point. It is of course understood that if desired, screw spikes, such as 56, may be inserted in the pockets 52 adjacent the channel 40, although this arrangement 70 is not necessary because of the wedging relation between the crossing member and the rail at that point.

Each of the crossing members 28 is further formed with an extending flange 62 to retain and 75 to prevent displacement of an insulation strip 64

disposed between the legs 36 of the members of the two series adjacent the rails 6 and 8.

The crossing members 30 are of a construction quite similar to the crossing members 28 and comprise an upper top plate 66 having anti-skid means, such as the buttons 68, the top plate 66 being formed with downwardly depending legs or flanges 70 corresponding to the legs or flanges 36 of the plates 28 and having a series of pockets 52 therein for supporting these plates upon the 10 stringers, such as 72 and 74. These crossing members 30 are likewise formed with lugs or extensions 76 adapted to engage beneath the head 18 of the rails 6 and 8, whereby the same may be secured in wedged relation therewith as by means 15 of screw spikes 56 received in the pockets 52. If desired, or because of interfering rail joints, screw spikes 56 may be introduced into the pockets 52 adjacent the lugs 76 for securing the crossing members to the stringers 74 at that point as 20 explained for the crossing member 28.

In the embodiment disclosed in Figures 1 and 2 of the drawings, the tracks 2 and 4 have a crossing of similar construction, and the intervening space therebetween may be filled as by means of 25 a concrete slab 78, the corners of which may be reinforced as by means of the angle irons 80, this concrete slab and the angle irons 80 being at substantially the same level as the top plate 66 of the crossing members 80 of the adjacent tracks. 30 The approach 81 to the crossing may comprise a concrete slab 83 reinforced at the corner by an angle iron 85 at substantially the level of the crossing members 30.

If desired, the crossing 26 may include end 35 plates 82 formed with an inclined top plate portion 84 having a downwardly depending leg or flange 86 adjacent which is provided one or more pockets 88 adapted to provide a support for these plates upon adjacent stringers, these end plates 40 being secured to these stringers as by means of screw spikes 56 passing downwardly through openings 90 formed in the lower supporting wall of these pockets 88, the head 60 of these screw spikes being disposed within the cavity formed by 45 these pockets.

In Figure 7 of the drawings, a crossing, generally referred to as 92, may be formed in accordance with the hereinbefore described crossing 26, and comprises series of members 94 and 96 secured upon stringers, such as 98, between rails, as for example the rail 100, which is secured upon the cross ties 102. A series of crossing members 104 may likewise be provided, these members being disposed adjacent the outer edge 50 of the rails 100 and being secured to stringers, such as 106, which in turn are supported upon the cross ties 102. The approach plates 108 correspond to the approach plates 82 of the hereinbefore described embodiment, and may likewise be provided in association with the cross members 94, 96 and 104, as disclosed.

The crossing members 94, 96 and 104 correspond essentially with the crossing members 26, 28 and 30, of the embodiment shown in Figure 1 of the drawings, and vary therefrom only as to the structure provided for securing them to the stringers. As disclosed in Figure 10 of the drawings, the edge of the crossing members 94 adjacent the inner or gauge edge of the rail 100 is formed with a channel-shaped portion 110 having spaced lugs 112 projecting therefrom which are adapted to engage beneath the head of the rail 100.

The crossing members 94 and 96 are of sim- 75

ilar construction and are formed with a plurality of pockets 114 adjacent each of the corners thereof, these pockets 114 having a bottom wall 116 spaced in relation to the top plate 118 and being apertured as at 120 to receive the shank of a screw spike 122. Adjacent each of the pockets 114, these crossing members are formed with spaced walls 124 depending downwardly from the top plate 118 and terminating in the support plate 126 extending therebetween and being formed integral with the vertical wall 128 of the channel portion 110 or with a corresponding wall depending from the plate 118 at other portions of the crossing member. The supporting plate 126 is formed with an aperture 130 in alignment with the aperture 120 through which the shank of the screw spike 122 passes, this screw spike shank passing downwardly and into the stringer disposed therebelow for securing the crossing members thereto at that point. Each of the crossing members 94 and 96 is likewise formed with an outwardly disposed flange 132 corresponding to the flange 62 of the crossing members 26 and 28, which overlies the insulation strip 134 disposed between these crossing members and which is supported upon the stringers 98.

The crossing members 104 are of somewhat similar construction to the crossing members 30 with the exception that the same are formed with pockets 136, corresponding to the pockets 114, and support plates 138 directly therebeneath which are integral with flanges 140 depending from the edge of the top plate 142. These support plates 138 are reinforced by integral spaced walls 144 extending to the top plate 142, this construction being all in accordance with the construction of the plates 94 and 96.

The present invention further comprehends a novel crossing between tracks in a multiple track crossing. As disclosed in Figure 11 of the drawings, an embodiment selected to illustrate the present invention is shown as comprising a crossing 146 disposed between rails 148 and 150 of adjacent tracks, these rails 148 and 150 being supported on and secured to the cross ties 152 and 154, respectively. The crossing 146 comprises a series of crossing members 156 and 158 corresponding essentially to the crossing members 104 of the embodiment shown in Figure 7 of the drawings, and are formed with spaced lugs 160 and 162 adapted to extend beneath and engage the head of rails 148 and 150, respectively. These crossing members 156 and 158 are supported at their inner edge upon the stringers 164 and 166 which are disposed adjacent the rails 148 and 150 and are secured to the cross ties 152 and 154, respectively. Their outer edge is supported upon stringers 168 and 170 of somewhat wider construction than the corresponding stringers 164 and 166, and which are in turn secured to the cross ties 152 and 154, respectively.

The crossing 146 further includes a series of crossing members 172 which are supported on the stringers 168 and 170 and span therebetween. These crossing members 172 are formed as disclosed in Figure 15 of the drawings, and are provided along their longitudinal edges with securing means, generally referred to as 174. This corresponds with similar structure as shown in Figures 8, 9, and 10 of the drawings. It is of course understood, however, that such securing means 174 may correspond with the securing means disclosed in the embodiment shown in Fig-

ures 1 to 6 inclusive. The crossing members 172 are likewise provided with outwardly extending flanges 176 and 178 adapted to overhang insulation strips 180 and 182 which are supported upon the stringers 168 and 170, respectively, these strips 180 and 182 likewise being engaged by overhanging flanges 184 and 186 provided at the outer edge of the crossing members 156 and 158, respectively.

The crossing 146 between the rails of adjacent tracks may be of any desired height, depending upon the stringers selected for supporting the same upon the cross ties 152 and 154, whereby the same may be adjusted to any height corresponding to the height of the rails 148 and 150, the top of this crossing being substantially at the level of the rails 148 and 150 and being formed, if desired, with the anti-skid means, including buttons 188.

In Figure 12 of the drawings is disclosed an alternative construction for a crossing between the rails 148 and 150 of adjacent tracks, this crossing, generally referred to as 147, including a series of members 190 and 192 corresponding to the members 156 and 158, respectively, of the embodiment shown in Figure 11 of the drawings. This crossing 147 further includes a series of crossing members 194 corresponding to the crossing members 172.

In this embodiment, the inner edge of the crossing members 190 and 192 is supported upon stringers 196 and 198 which in turn are supported upon and secured to cross ties 152 and 154, respectively. The outer edge of these members 190 and 192, however, is supported upon and secured to spaced tie members 200, which may be supported upon and secured to the cross ties 152 and 154. The crossing members 194 are suitably disposed between the members 190 and 192 and are secured to and supported upon the tie members 200. As in the previously disclosed embodiment, the insulation strips 202 and 204 are disposed between crossing members 190 and 194, and crossing members 194 and 192, respectively, the same being held in place as by means of suitable flanges formed on these members, all in accordance with the previously discussed crossing members 156, 158 and 172.

In Figure 13 of the drawings is disclosed a still further crossing, generally referred to as 206, disposed between rails 148 and 150 of adjacent tracks, these rails being supported upon the cross ties 152 and 154. In this embodiment, the crossing comprises a series of end crossing members 208 and 210, and series of crossing members 212 and 214 disposed therebetween. The crossing 206 includes stringers 216, 218, 220, 222 and 224 disposed between the rails 148 for supporting the plates 208, 210, 212 and 214. The stringers 216 and 224 are secured to the cross ties 152 and 154, respectively, adjacent the rails 148 and 150, while the stringers 218 and 222 are supported in part by the cross ties 152 and 154, respectively, and in part by spaced tie members 226 disposed between cross ties 152 and 154. The stringer 220 is supported upon and secured centrally of the tie members 226. The crossing members 208 and 210 are substantially of similar construction to the crossing members 156 and 158, respectively, of the embodiment shown in Figure 11 of the drawings, and have flanges overlying insulation strips 228 and 230, respectively. The crossing members 212 and 214 correspond essentially with the crossing members 172 and 194 and are formed respectively, with flanges overhanging insulation

strips 232 and 234, respectively. The crossing members 212 and 214 correspond essentially with the crossing members 172 and 194 and are formed respectively, with flanges overhanging insulation

strips 228 and 230 as likewise an insulation strip 232 disposed therebetween and supported on the stringer 220.

In the embodiment disclosed in Figures 11, 12, 5 and 13 of the drawings, it is of course understood that the crossing members may be formed in accordance with either of the embodiments heretofore disclosed, and may be of any desired length and width to suit the occasion, as for example, when the rails 148 and 150 are at varying distances apart or the varying lengths of the cross ties necessitate variations in width or length of the individual cross members.

From the above disclosure, it will be quite apparent that the crossing members are particularly designed for withstanding heavy truck loads and may be either of the cast plate type or formed from rolled plates and shapes welded together. It will likewise be recognized that any one of these crossing members may be easily and readily applied and removed, and the entire crossing construction is well adapted to be used in association with rails of various heights, it being necessary only to vary the depth of the stringer members used for any particular rail height. The stringers are of such a height that when the crossing members are inserted at a vertical angle so that the legs or extensions thereof engage under the head of the rails, further angular movement of the crossing members into their substantially horizontal operative position effects a wedging of the same with these rails, so that when the crossing members are held in this operative position by means of the screw spikes, the same are not readily displaced or dislodged by the heavy loads passing thereover.

While I have herein described and upon the drawings shown illustrative embodiments of the invention, it is to be understood that the invention is not limited thereto, but may comprehend other constructions, arrangements of parts, details and features without departing from the spirit of the invention.

I claim:

1. In a railway crossing or the like, the combination of spaced rails, crossing members disposed adjacent said rails, and means adjacent said rails and extending in substantially parallel relation thereto for providing the sole support for 50 said crossing members, said crossing members having longitudinally spaced lugs engaging under the head of said rails in wedging relation when in position on said supporting means, and means for securing said crossing members to said supporting means in said wedging relation.

2. In a railway crossing or the like, the combination of spaced rails, a series of crossing members disposed adjacent said rails, means independent of said rails supported on cross ties and 60 extending in substantially parallel relation to said rails for supporting the longitudinal edge portions of said members adjacent said rails, said members being supported on said supporting means and having means extending laterally 65 thereof and engaging under the head of said rails in wedging relation, and means common to each of said series and extending in substantially parallel relation to said rails for maintaining and supporting opposite longitudinal edge portions of 70 said crossing members in said wedging relation.

3. In a railway crossing or the like, the combination of spaced rails mounted on spaced ties, a series of crossing members disposed adjacent each of said rails, means disposed on said ties for 75 supporting said members between said rails, said

means comprising stringers supported on said ties and disposed adjacent said rails and a stringer common to both series of members disposed on said ties between said first-named stringers, said crossing members having means engaging with 5 said rails whereby the same are in wedged relation therewith when disposed in operable position on said supporting means at substantially the level of said rails, and means for securing said members to said stringers in said wedged relation 10 with said rails.

4. In a railway crossing or the like, the combination of spaced rails mounted on spaced ties, a series of crossing members disposed adjacent each of said rails, means disposed on said ties for supporting said members between said rails, said means comprising stringers supported on said ties and disposed adjacent said rails and a stringer common to both series of members disposed on said ties between said first-named 20 stringers, said members being provided with a channel adjacent the inner or gauge edge of said rails to provide clearance for the wheel flanges of passing trains, said members having means adjacent said channel engaging with said rails 25 whereby the same are in wedged relation therewith when disposed in operable position on said supporting means at substantially the level of said rails, and means for securing said members in said wedged relation with said rails. 30

5. In a railway crossing or the like, the combination of spaced rails mounted on spaced ties, a series of crossing members disposed adjacent each of said rails, means disposed on said ties for supporting said members on said ties and between said rails, said means comprising stringers supported on said ties and disposed adjacent said rails and a stringer common to both series of members disposed on said ties between said first-named stringers, said crossing members having means engaging with said rails whereby the same are in wedged relation therewith when disposed in operable position on said supporting means at substantially the level of said rails, means for securing said members in 40 said wedged relation with said rails, and insulating means between said series. 45

6. In a railway crossing or the like, the combination of spaced rails mounted on spaced ties, a series of crossing members disposed adjacent each of said rails, means for supporting said members on said ties and between said rails, said crossing members having means engaging with said rails whereby the same are in wedged relation therewith when disposed in operable 50 position on said supporting means at substantially the level of said rails, means for securing said members in said wedged relation with said rails, the members of each series having laterally extending flanges and depending marginal flanges engaging said supporting means, and insulating means between said series, said insulating means being engaged by said flanges and said supporting means to prevent dislodgment 55 of the same. 60

7. In a railway crossing or the like, the combination of spaced rails mounted on spaced ties, a series of crossing members disposed adjacent each of said rails, means supported on said ties between said rails and providing the sole support for said crossing members, said members being provided with a channel adjacent the inner or gauge edge of said rails to provide clearance for the wheel flanges of passing trains, said members having longitudinally spaced lugs adjacent said 70 75

- channel and extending laterally thereof engaging with said rails whereby the same are in wedged relation therewith when disposed in operable position on said supporting means at substantially the level of said rails, means for securing said members to said supporting means in said wedged relation, and insulating means between said series. 5
8. In a railway crossing or the like, the combination of spaced rails mounted on spaced ties, a series of crossing members disposed adjacent each of said rails, means for supporting said members on said ties and between said rails, said members being provided with a channel adjacent the inner or gauge edge of said rails to provide clearance for the wheel flanges of passing trains, said members having means adjacent said channel engaging with said rails whereby the same are in wedged relation therewith when disposed in operable position on said supporting means at substantially the level of said rails, means for securing said members in said wedged relation with said rails, the members of each series having laterally extending flanges and depending marginal flanges engaging said supporting means, and insulating means between said series, said means being engaged by said flanges and said supporting means to prevent dislodgement of the same. 15
- 30 9. In a railway crossing or the like, the combination of spaced rails mounted on spaced ties, a series of crossing members disposed adjacent each of said rails, means supported on said ties between said rails and providing the sole support for said crossing members, said crossing members having means engaging with said rails whereby the same are in wedged relation therewith when disposed in operable position on said supporting means at substantially the level of said rails, means for securing said members to said supporting means in said wedged relation, a series of crossing members disposed at the outer edges of said rails and having means engaging with said rails whereby the same are in wedged relation therewith when in operable position, means supported on said ties providing the sole support for said last-named crossing members, and means for securing said last-named crossing members to said last-named supporting means in said wedged relation. 45
- 50 10. In a railway crossing or the like, the combination of spaced rails mounted on spaced ties, a series of crossing members disposed adjacent each of said rails, means supported on said ties providing the sole support for said members between said rails, said means comprising spaced stringers disposed in substantially parallel relation to said rails, said members being provided with a channel adjacent the inner or gauge edge of said rails to provide clearance for the wheel flanges of passing trains, said members having spaced lugs adjacent said channel extending laterally thereof and engaging with said rails whereby the same are in wedged relation therewith when disposed in operable position on said supporting means at substantially the level of said rails, means for securing said members in said wedged relation with said rails, a series of crossing members disposed at the outer edges of 60 said rails and having spaced lugs extending laterally thereof and engaging with said rails whereby the same are in wedged relation therewith when in operable position, means supported on said ties providing the sole support for said last-named members, said supporting means 70 comprising spaced stringers disposed in substantially parallel relation to said rails, and means for securing said crossing members to said stringers. 75
11. In a railway crossing, the combination of spaced rails, crossing members disposed on both sides of said rails, said members having means directly engaging with and under the head of said rails whereby the same are in wedged relation with said rails when in an operable position substantially at the level of said rails, and means for supporting and holding said members in said operable position, said means comprising spaced stringers disposed on said ties and in substantially parallel relation to said rails. 15
12. A crossing member comprising a top plate portion having spaced apertured depressed pockets, and spaced supporting legs disposed adjacent said pockets having an integral inwardly apertured flange extending therebetween. 20
13. A crossing member comprising a top plate portion having spaced apertured depressed pockets, supporting legs disposed adjacent said pockets having an inwardly apertured flange, and reinforcing means integral with and extending between said top plate and flanges. 25
14. A crossing member comprising a top plate portion having spaced apertured depressed pockets, supporting legs disposed adjacent said pockets having an inwardly apertured flange, and spaced walls integral with and extending between said top plate and flanges. 30
15. In a railway crossing, the combination of a plurality of tracks, each of said tracks comprising spaced ties, spaced rails supported thereon, spaced stringers disposed on said ties adjacent a rail of each track, a crossing between tracks including a series of crossing members disposed adjacent a rail of each track and secured to said stringers, and a series of crossing members between said first-mentioned series spanning between the ties of said tracks and secured to one of said spaced stringers of each track. 35
16. In a railway crossing, the combination of a plurality of tracks, each of said tracks comprising spaced ties, spaced rails supported thereon, a stringer secured to said ties adjacent a rail of each of said tracks, spaced tie members supported on and spanning between the ties of said tracks, and a crossing between said tracks secured to said stringers and last-mentioned ties. 45
17. A crossing member comprising a top plate portion having an apertured depressed pocket, and a marginal flange having an inwardly disposed support plate portion beneath said pocket provided with an aperture in alignment with the aperture of said pocket. 55
18. A crossing member comprising a top plate portion having an apertured depressed pocket, and a marginal flange having an inwardly disposed support plate portion beneath said pocket provided with an aperture in alignment with the aperture of said pocket, and means extending between the top plate and support plate for reinforcing the same. 60
19. A crossing member comprising a top plate portion having an apertured depressed pocket, and a marginal flange having an inwardly disposed support plate portion beneath said pocket provided with an aperture in alignment with the aperture of said pocket, and spaced walls extending between said plate portions. 65
20. In a railway crossing or the like, the combination of spaced rails mounted on spaced ties, a series of crossing members disposed adjacent 70

each of said rails, means disposed on said ties for supporting said members between said rails, said means comprising stringers supported on said ties and disposed adjacent said rails and a stringer common to both series of members disposed on said ties between said first-named stringers, said stringers providing the sole support for said crossing members, said crossing members having means engaging with said rails whereby the same are disposed in operable position on said supporting means at substantially the level of said rails, and means for securing said members to said stringers in engaging relation with said rails.

21. In a railway crossing or the like, the combination of spaced rails mounted on spaced ties, a series of crossing members disposed adjacent

each of said rails, means disposed on said ties for supporting said members on said ties and between said rails, said means comprising stringers supported on said ties and disposed adjacent said rails and a stringer common to both series of members disposed on said ties between said first-named stringers, said stringers providing the sole support for said crossing members, said crossing members having means engaging with said rails whereby the same are disposed in operable position on said supporting means at substantially the level of said rails, and means for securing said members in engaging relation with said rails, and insulating means between said series.

15

WILLIAM C. HEDGCOCK.
